UNITED STATES PATENT OFFICE.

BANCROFT G. BRAINE, OF NEW YORK, AND WILLIAM J. BRADLEY, OF TROY, NEW YORK, ASSIGNORS TO THE RAIL JOINT COMPANY, OF NEW YORK, N. Y., A CORPORATION OF NEW YORK.

ROLLED SHOE-ANGLE.

1,110,529.

Specification of Letters Patent.

Patented Sept. 15, 1914.

Application filed June 11, 1914. Serial No. 844,570.

To all whom it may concern:

Be it known that we, BANCROFT G. BRAINE and WILLIAM J. BRADLEY, citizens of the United States, residing, respectively, at New York and Troy, in the counties of New York and Rensselaer, respectively, and State of New York, have invented certain new and useful Improvements in Rolled Shoe-Angles, of which the following is a specification.

This invention relates to rail joints of the Weber type, and particularly to an improvement in the shoe angle thereof.

Accordingly, the primary object of the invention is to provide a novel design of shoe angle which can be economically and expeditiously rolled in the passes of a rolling mill, while at the same time having a structural formation adapting it to the use of screw spikes in place of the ordinary cut spikes for joint fastening purposes.

A further object of the invention is to provide a shoe angle having substantial and symmetrical bearings for the heads of screw spikes at both the outside and inside of the joint, these bearings being of such character as to afford firm and rigid supports for the screw spike heads at their outer and inner sides. In this connection, the present invention makes special provision for the outer bearings for the heads of the screw spikes located at the inside of the joint by a novel form of toe-flange at the inner edge portion of the shoe angle base plate. This flange is produced by the rolling operation, and without requiring special preparation of any of the passes to hold a larger quantity of metal than is ordinarily taken care of by the usual passes for rolled shoe angles. That is to say, the said rolled inner toe-flange, of the new shoe angle shape, is of the same thickness as the base of the shoe angle, thereby enabling the metal to be more readily handled and distributed in the rolls, and in fact permitting the base of the shoe angle to be rolled flat up to near the final passes wherein it can be bent up, at its inner edge, to produce the outer bearing referred to for screw spike heads.

With these and other objects in view which will be apparent to those familiar with this art, as the specific nature of the improvement is better understood, the same consists in the novel shoe-angle design here-

in after more fully described, illustrated, and 55 claimed.

Though susceptible of some structural modification without departing from the scope of the invention, a preferred and practical embodiment is shown in the accompanying drawings in which—

Figure 1 is an end view, partly in section, of a Weber type of rail joint having the improved shoe-angle constructed in accordance with the present invention. Fig. 2 is a detail in perspective of the improved shoe-angle, indicating by full and dotted lines, the feature of the design permitting the shoe angle being rolled with its base flat throughout for use with the ordinary cut spikes, as well as with its inner edge rolled up to produce the toe-flange which provides an outer bearing for the heads of the screw spikes located at the inside of the joint.

Like reference characters designate corresponding parts in the several figures of the drawings.

To illustrate the preferable embodiment of the invention, the same is shown in the drawings applied to the well known type of Weber rail joint which includes in its organization the rail 1, a side angle bar 2 fitting the fishing space of the rail at the inside of the joint, a side channel bar 3 fitting the fishing space of the rail at the outside 85 of the joint, a shoe-angle 4, and a wooden or equivalent compressible filler block 5 interposed between the upright member 6 of the shoe angle and the outer side of the channel bar 3. The filler block 5 is usually and preferably of a reversible type so that it is reversible end for end and top for bottom, and the joint structure illustrated includes the usual joint bolts 7 serving to clamp the parts together and to the rails in 90 the well known manner and for the usual purpose.

The distinctive improvement contemplated by the present invention resides in the novel structural characteristics of the 100 shoe-angle 4. This shoe angle preserves the conventional structural and functional characteristics of the shoe-angle employed in the Weber type of rail joint, and essentially includes the upright member or bolting plate 105 6 formed integrally with a rail-supporting base plate 8 which is of greater width than the rail bases so as to extend entirely be-

neath the latter and project beyond the inner edges of the rail flanges. Furthermore, the shoe-angle also retains the usual structural feature of having formed therewith, at the junction of the upright member 6 and the base plate 8, an outwardly projecting spiking toe or flange 9. This spiking toe or flange 9 is provided therein with the requisite number of spike receiving holes 10, and is formed at its upper side with a longitudinal depression 11 producing a chamfered or beveled bearing seat at the top of each spike receiving hole 10. The bearing seat, thus provided, receives the conical under side 12 of the head 13 of a screw spike 14, so that the heads of the spikes located at the outside of the joint are all provided with a symmetrical bearing supporting both the inner and outer sides thereof.

In order that the entire shoe-angle may be completed by the rolling operation in the passes of a rolling mill, and the outer bearing formed for the heads of the spikes at the inside of the joint, the same amount of metal is carried throughout the base plate 8 so that the same is of uniform thickness from one edge to the other. This enables the metal to be readily handled and distributed in the rolls, and at the same time admits of the formation of an inner toe-flange 15 by the final passes of the mill.

This toe-flange 15 is the distinguishing and important feature of the present invention. As stated, it is bent into its final form by the rolling passes of the mill without making special provision to care for a larger quantity of metal than usual in the rolling of the ordinary shoe angle. Accordingly, the shoe-angle may be rolled in its usual form having the base member thereof flat throughout, as indicated by the dotted lines in Fig. 2 of the drawings, to adapt it for use with the ordinary cut spikes, but to adapt it for screw spikes, according to the present invention, the base member of the angle is rolled flat, up to near the final passes of the mill, these final passes being designed to take hold of the inner edge thereof and deflect the same upwardly to one side of the flat plane of said member. By this operation a reverse bend is given to said inner edge with the result of producing the toe-flange 15 having an upper inclined

bearing surface 16 which is disposed at the same angle as the angle of the under surface 55 of the screw-spike head.

A spike receiving hole 17 pierces the rolled inner edge portion of the base member of the shoe angle to receive a screw spike 18 having the usual spike head 19 provided with a conical under surface 20 adapted to have a symmetrical bearing upon the rail flange and said upper inclined bearing surface 16 of the toe flange 15. Hence, the said spike head has both an inside and an outside 65 bearing which firmly and rigidly supports the same against outward tilting by lateral pressure imposed thereon.

Changes in the form, proportion, and minor details of construction as falling within the scope of the appended claims may be resorted to without departing from the spirit or sacrificing any of the advantages of the invention.

We claim:

1. A shoe angle for rail joints whose base member is provided with an upwardly bent rolled inner edge portion having a spike receiving hole and an upper inclined spike-head bearing surface disposed at the outer 80 side of said hole.

2. A shoe angle for rail joints provided at the inner edge portion of its base member with a rolled toe-flange bent to present at its upper side an inclined outer spike-head bearing.

3. A shoe angle for rail joints provided at the inner edge of its base member with a spike hole and with a rolled toe-flange having a reverse bend to present an inclined 90 spike-head bearing beyond the outer side of the hole.

4. A shoe angle for rail joints provided at the inner edge portion of its base member with an upwardly bent rolled toe-flange of 95 the same thickness as the remaining portion of the base member and presenting at its upper side an outer spike-head bearing.

In testimony whereof we hereunto affix our signatures in the presence of two witnesses.

BANCROFT G. BRAINE.
WILLIAM J. BRADLEY.
